UNITED STATES PATENT OFFICE.

REINHOLD BARTELL, OF NEWARK, NEW JERSEY, ASSIGNOR TO BARTELL IMPROVED SHIRT COMPANY, OF NEW YORK, N. Y., A CORPORATION OF NEW YORK.

SHIRT.

1,050,715.

Specification of Letters Patent. Patented Jan. 14, 1913.

Application filed December 27, 1910. Serial No. 599,426.

To all whom it may concern:

Be it known that I, REINHOLD BARTELL, a citizen of the United States, and a resident of Newark, in the county of Essex and State 5 of New Jersey, have invented certain Improvements in Shirts, of which the following is a specification.

This invention relates to new and useful improvements in shirts, and has for its object 10 to provide a device of this general character of a simple and comparatively inexpensive nature having novel and improved means capable of engagement with trousers or the like to hold the same in proper position, the engagement with the trousers or 15 the like serving to effectually prevent a pull or hiking up of the shirt as is generally the case in ordinary shirts.

The invention consists in certain novel 20 features of the construction, and combinations and arrangements of the several parts of the improved shirt, whereby certain important advantages are attained, and the device is rendered simpler, less expensive 25 and otherwise better adapted and more convenient for use, all as will be hereinafter fully set forth.

The novel features of the invention will be 30 carefully defined in the claim.

In order that my improvements may be 35 the better understood, I will now proceed to describe the same with reference to the accompanying drawings, wherein—

Figure 1 is a front view of a shirt constructed in accordance with my invention; Fig. 2 is an enlarged fragmentary view illustrating certain details of the trouser engaging means; Fig. 3 is a sectional view taken on the line 3—3 of Fig. 2, looking in the direction of the arrow; Fig. 4 is a sectional view taken on the line 4—4 of Fig. 2; Fig. 5 is a view similar to Fig. 2, looking from the inside of the shirt; Fig. 6 is a view similar to Fig. 2 illustrating the trouser engaging 40 means in an incompletely state; and Fig. 7 is a fragmentary view in perspective showing a shirt constructed in accordance with the invention in operative engagement with trousers.

In these views, 10 denotes a dress shirt 45 which may be of any ordinary or preferred construction but herein shown as a coat shirt having secured to the inner face thereof by the stitching 12 at predetermined points about the waist line, the vertically extended

reinforcement strips 11. While the reinforcement strips 11 are herein shown as secured to the shirt proper by stitching 12, it is thought to be obvious that such reinforcement strips may be glued or otherwise secured to the shirt in lieu of such stitching. 60

To the outer surface of the shirt 10 above each of the reinforcement strips 11 is secured the vertically extended rectangular strip 13 such attachment of the strip with the shirt 65 being through the medium of the parallel lines of stitching 14 closely adjacent to each other and positioned substantially centrally of such strip 13 and terminating a predetermined distance from the opposite ends 70 thereof. After the attachment of the reinforcement strips 11 and the outer strip 13 to the shirt, a slot or elongated cut 15 is made through both of the strips and the shirt and the free marginal portions 16 of 75 the outer strip 13 are passed through the slot 15 and secured to the inner face of the shirt by the stitching 17 as is particularly shown in Fig. 5. While the free marginal portions 16 may be passed through the slot 15 80 in any desired manner it has been found to be of great advantage to grasp the ends of the strip 13 at the points indicated as *a* and to force these points through the slot 15 and then give an opposite pull thereto which 85 operation causes a proper adjustment of the marginal portions 16 of this strip 13 as shown in Fig. 5. This folding of the strip 13 produces a rounded edge, which is greatly 90 to be desired in a device of this character. 95 After this operation the elongated slot or opening is divided into button-holes by the cords 18 or folded strips 19 and it is thought to be obvious that the slot may be subdivided into as many button-holes as the requirements of practice may dictate.

In Fig. 7, the operation of the invention is thought to be fully disclosed. In this view 100 22 denotes the trousers provided with a button 21 or other suitable attaching means which is adapted to be accommodated within any one of the button-holes 20 hereinbefore referred to and it is thought to be obvious that the trousers may be lowered or raised to any desired height for the comfort or neat 105 appearance of the wearer by placing the button 21 within the requisite button-hole 20. This engagement of the shirt with the trousers or the like while affording an effective support for the trousers also makes the shirt 110

lie close to the body of the wearer and effectually prevents pulling or hiking up of the shirt which, in the ordinary line of shirts, greatly interferes with the enhancing effect 5 of the garment.

From the foregoing description of my invention, it will be seen that I have produced a garment which is capable of quick and ready engagement with trousers to effect 10 tually support the same and it will also be obvious from the above description that the invention is susceptible of considerable modification without material departure from the principles and spirit of the invention, and 15 for this reason I do not desire to be understood as limiting myself to the precise formation and arrangement of the several parts, as herein set forth, in carrying out my invention in practice.

Having thus described my invention, what 20 I claim as new and desire to secure by Letters Patent is:

A shirt having a strip secured to one side thereof and a second strip secured to the opposite side of the shirt above the first 25 named strip, said shirt and strips having a slot there through, the marginal portions of one of the strips being drawn through the slot and secured to the exposed face of the second strip and means for subdividing the 30 slot into a series of button holes.

Signed at New York, in the county of New York and State of New York, this 23rd day of December, A. D. 1910.

REINHOLD BARTELL.
